UNITED STATES PATENT OFFICE.

LANSING JORALEMON AND NELSON R. MABEY, OF GLOVERSVILLE, N. Y.

CAR-COUPING.

SPECIFICATION forming part of Letters Patent No. 296,579, dated April 8, 1884.

Application filed February 11, 1884. (No model.)

To all whom it may concern:

Be it known that we, LANSING JORALEMON and NELSON R. MABEY, citizens of the United States, and residents of Gloversville, in the 5 county of Fulton and State of New York, have invented certain new and useful Improvements in Car-Couplings; and we do hereby declare that the following is a full, clear, and exact description of the invention, which will enable others 10 skilled in the art to which it appertains to make and use the same, reference being had to the accompanying drawings, which form a part of this specification, and in which—

Figure 1 is a perspective view of our improved car-coupling. Fig. 2 is a front view of the same. Fig. 3 is a longitudinal vertical section. Fig. 4 is a longitudinal horizontal section, and Figs. 5 and 6 are detail views of the coupling-bolt and the sliding catch.

20 Similar letters of reference indicate corresponding parts in all the figures.

Our invention has relation to that class of car-couplings in which a bolt or bar having enlarged and shouldered heads is engaged by 25 a catch in the draw-head; and it consists in the improved construction and combination of parts of the same, as hereinafter more fully described and claimed.

In the accompanying drawings, the letter A 30 indicates the draw-head, which has the same outward appearance as the draw-heads used in the common pin-and-link coupling, but has a vertical recess, B, in its outer portion, opening at the top, and forming at the foremost ends of 35 its sides two vertical ways, C, the lower ends of which are stopped by a cross-piece, D, extending over the foremost portion of the lower end of the recess.

E is a plate fitting over the upper open end 40 of the recess, and resting with its edges upon the edges of the recess, and the under side of this plate is provided at its forward end with a downwardly-projecting plate, F, the edges G of which are rabbeted to slide in the vertical 45 ways in the forward end of the recess, while its lower end forms a notch or recess, H, the sides of which form two inwardly-projecting lugs, I, beveled at their forward sides, as shown at J. This plate slides vertically across the 50 mouth of the draw-head, the upper edge of the notch in the lower portion of the plate being at a level with the upper edge of the mouth,

and for the purpose of guiding and bracing the plate a longitudinal rib, K, is secured to the under side of the top plate, from the rear 55 end of which rib projects a vertical guide-bar, L, which bears with its rear side against the rear side of the recess or bore, guiding the vertical plate in sliding in its ways, and serving together with the rib as a brace when draft is 60 applied to the coupling-bar, which bears with its shoulders against the inner sides of the beveled lugs, forcing the lower end of the sliding plate forward, and thus forcing its upper end back, which again in turn will throw the strain 65 upon the rib, which will bear against the rear side of the recess, and the strain thus being divided upon this number of parts and over such a space, the entire sliding frame (the vertical plate, the top plate, the rib, and the vertical bar) will be prevented from binding in 70 its recess, sliding freely in the same regardless of the strain of the coupling-bar upon it. The coupling-bar M is preferably flat, and forms at each end two laterally-projecting shoulders, 75 cut off beveled upon their upper and lower sides, while the upper side of the end of the bar is not cut off, thus forming a rib passing through the upper beveled side of the head formed upon each end of the bar, and the said 80 rib serves, in entering the draw-head between the two beveled lugs upon the sliding plate, to guide the bar, especially while coupling cars standing upon a curve or standing obliquely to each other for any other reason.

For the purpose of raising the sliding plate in uncoupling the bar, a lever, N, forming a handle at its outer end, is pivoted at its inner end between two upright lips, O, projecting upward from one edge of the draw-head, and 90 passes through a slot, P, having its upper and lower ends rounded, in an upright block, Q, upon the top plate.

The operation of our car-coupling will be readily understood from the foregoing description, taken in connection with the accompanying drawings, without further explanation.

Having thus described our invention, we claim and desire to secure by Letters Patent of the United States—

100 The combination of the draw-head, forming a vertical recess, forming vertical ways at its forward corners, closed at their lower ends by a cross-piece, with a top plate resting upon the

edges of the recess, and forming a forward sliding plate having a recess at its lower end, forming forwardly-beveled lugs at its sides, and forming a longitudinal rib upon its under side 5 and a vertical guide-bar at the rear end of the rib bearing against the rear side of the recess, as and for the purpose shown and set forth.

In testimony that we claim the foregoing as

our own we have hereunto affixed our signatures in presence of two witnesses.

LANSING JORALEMON.
NELSON R. MABEY.
